UNITED STATES PATENT OFFICE.

LUKE TOZER, OF IOLA, KANSAS.

OIL-BURNER.

1,073,306.

Specification of Letters Patent. Patented Sept. 16, 1913.

Application filed January 13, 1913. Serial No. 741,798.

To all whom it may concern:

Be it known that I, LUKE TOZER, a citizen of the United States, residing at Iola, in the county of Allen and State of Kansas, have invented certain new and useful Improvements in Oil-Burners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to oil burners, and more particularly to a device of that class adapted for use in stoves or furnaces and wherein fuel oil is converted into gas and mixed with air to provide a combustible 20 fuel, the principal object of the invention being to provide a structure for converting the liquid into gas and securing a proper mixture with the oxygen in the air admitted to the burner to provide the desired fuel gas.

25 In accomplishing this object I have provided the improved details of structure hereinafter described and illustrated in the accompanying drawings, wherein:—

Figure I is an elevation of a burner constructed according to my invention, shown in connection with an ordinary fire bowl, the latter being in section to illustrate its combination with the burner. Fig. II is a central, vertical section of the burner and fire bowl. Fig. III is a horizontal section on the line III—III, Fig. II. Fig. IV is an inverted plan view of the burner base.

Referring more in detail to the parts:—
1 designates a fire bowl of any ordinary 40 construction adapted for use in stoves or furnaces, having a central bottom grate opening 2. Located in the bottom of the fire bowl, preferably on a seat 3, and completely covering the grate opening, is a base plate 4 upon which the burner is supported. The plate 4 is imperforate except for a central aperture 5 crossed by a bar 6 which also has a central aperture 7. Supported on the plate 4 within the fire bowl, 45 and preferably confined by a ring flange 8 on the top of said plate, is a barrel 9 which preferably tapers toward the top and has legs 10 adapted for supporting a cap 12 and for providing ports 11 for the delivery 50 of air from the interior of the barrel. The cap 12 preferably consists of a solid, cylin-

drical piece of metal having a central bore 13 carrying a pipe 14 which is adapted for projection through the barrel 9 and the aperture 7 in the base plate and for threading into the supply pipe 15, so that the barrel 9 is clamped between the cap and base plate. The top of the cap is cupped to provide a generating chamber 16 and has bosses 17 on its upper edge and ribs 18 at 60 the sides for spacing a hood 20 which is loosely supported thereon.

The hood 20 preferably comprises an inverted cup which, when supported on the bosses 17 and spaced from the cap by the 70 ribs 18, allows the gas generated in the chamber 16 to pass down around the cap and mingle with the air delivered through the ports 11 to produce the fuel gas, the lower edge of the hood being located below 75 the lower edges of the ports 11 so that the gas and air mix above the annular outlet at the lower edge of the hood. The hood 20 may be provided with a handle 21 by which it may be removed from the cap 12, and the 80 barrel 9 is preferably provided with a bowl-shaped flange 22 to provide a receptacle into which oil may be delivered by overflow from the chamber 16 and ignited to heat the parts for initially generating gas.

85 In using the burner, presuming the parts to be constructed and assembled as described, oil is admitted through the supply pipe to the generating chamber and overflows said chamber into the bowl at the bottom of the barrel. This oil is then ignited and burns to heat the generator parts in order to secure an initial flow of gas, the supply being cut off as soon as sufficient quantity has been delivered into the bowl. The 90 oil in said bowl is then ignited to heat the parts and secure an initial generation of gas. As soon as the parts become sufficiently heated the supply is again turned on and the incoming oil is generated into gas 95 100 in the chamber 16 and this gas flows between the top of the chamber and down around the sides of the cap to mingle with air coming up through the bottom of the fire bowl and delivered through the ports 11 to 105 produce a suitable combustible fuel.

It is apparent that natural draft will draw the gas and air through their respective ports and assist in properly mixing the separate elements prior to their ignition as 110 the mixture leaves the generator. It is also apparent that as the oil supply pipe passes

through the interior of the barrel, and is at all times surrounded by cool incoming air, that the pipe does not become heated and, consequently, oil within the pipe will not 5 carbonize to clog or obstruct the passage, resulting in a free supply of oil at all times.

Having thus described my invention, what I claim as new therein and desire to secure by Letters-Patent, is:-

10 1. An oil burner comprising an open top barrel having side ports therein, a cap located above the barrel and having bosses on its upper edge and ribs on its outer face, and a hood seated on said bosses and depending around the body of the cap, the lower edge of the hood being extended below the barrel ports to provide an annular chamber and around the cap and around the ported part of the barrel, for the purpose 15 set forth.

15 2. An oil burner comprising a barrel having ports in its upper portion, a cap seated on said barrel and having a generating chamber in its upper face and a bore opening into said chamber, said cap being also provided with bosses on its upper edge and with ribs on its outer face, a hood seated on said bosses and spaced by said ribs, and a supply pipe fixed in the cap bore and extended through said barrel.

20 3. The combination with a fire bowl having a grate opening, of a plate covering the grate opening and having a central aperture, an apertured bar extending across said central aperture, a barrel supported on said plate and covering the aperture therein and having ports in its upper end, a cap supported on said barrel and having a generating chamber in its upper portion and a bore 25 opening into said generating chamber, a hood covering the cap and depending around the upper portion of the barrel, and a sup-

ply pipe fixed in said bore and extending through the barrel and through the aperture in the plate bar.

45 4. An oil burner comprising a barrel having legs on its upper edge and having side ports, a cap seated on said legs and having a generating chamber in its upper face and a bore opening into said generating chamber, said cap being provided with bosses on its upper edge and with ribs on its side face, a hood having a base supported on said bosses and spaced upwardly from the body of the cap and a side flange depending over 50 the body of the cap and below the side ports in the barrel and spaced by said ribs from the cap and barrel to provide an annular passage, and a supply pipe fixed in the cap bore and extending through the interior of 55 said barrel.

5. The combination with a fire bowl having a grate opening, of a plate supported on the bowl and covering the grate opening and having a central aperture, a bar integral 60 with the plate and extending through said aperture and having an aperture therein, a barrel seated on said plate and covering the plate aperture and having ports in its upper portion, a cap seated on said barrel and having a generating chamber in its upper portion and having a bore opening into the generating chamber, a pipe fixed in said bore and connected with said plate whereby the barrel is clamped between the cap and plate, 65 and a hood supported on the cap and depending around the ported portion of said barrel.

In testimony whereof I affix my signature in presence of two witnesses.

LUKE TOZER.
